**COMBINED MOLD AND PACKING TRAY
FOR A CONFECTION**

Robert W. Schumann, Brookfield, Wis., assignor to
W. R. Grace & Co., New York, N.Y.

Continuation-in-part of design application Ser. No.
20,534, Dec. 17, 1969. This application Feb. 25,
1971, Ser. No. 119,080

Term of patent 14 years

Int. Cl. D9—03

U.S. Cl. D9—240

FIG. 1

FIG. 2

FIG. 3

FIG. 4

FIG. 1 is a top plan view of a combined mold and packing tray for a confection showing my new design;

FIG. 2 is a sectional perspective view taken on the line 2—2 of FIG. 1;

FIG. 3 is a top plan view with the transparent sealed lid removed; and

FIG. 4 is an end elevational view thereof.

This application is a continuation-in-part of my earlier application Ser. No. 20,534 filed Dec. 17, 1969, and now abandoned.

I claim:

The ornamental design for a combined mold and packing tray for a confection, as shown and described.
